UNITED STATES PATENT OFFICE

2,455,682

SHELVING

Albert F. Kern, San Francisco, Calif.

Application December 26, 1945, Serial No. 637,209

5 Claims. (Cl. 211—147)

1

This invention relates to shelving, an object being to provide new and novel means whereby supporting metal posts located in convenient positions can be utilized for supporting shelves in any desired relationship.

It is a further object to provide shelf-supporting means which is simple, durable and efficient in construction and can be set up readily.

Another object is to provide a support which can utilize ordinary pipe sections as supporting posts, the present improvement being such that it may be mounted readily on the pipes.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing, the preferred form of the invention has been shown.

In said drawing,

Figure 1 is a front elevation of some shelves mounted on a supporting structure such as constitutes the present invention.

Figure 2 is a view partly in plan and partly in section showing several shelves and their connections with a post.

Figure 3 is a section on line 3—3, Figure 2.

Figure 4 is a top plan view of one of the supporting collars of the apparatus.

Figure 5 is a bottom plan view of one of the collar engaging or coupling units.

Referring to the figures by characters of reference, 1 designates one or more posts which can be in the form of pipes and each of these posts is extended through one or more collars 2 which can be held in any desired positions by means of set screws 3.

Each collar is provided with a flared annular portion 4 which cooperates with the post to define circular recess 5. Notches 6 are formed in the top edge of the collar and are preferably spaced apart equal distances as shown in Figure 4, it being preferred to make the notches with downwardly converging side walls 7.

In connection with each collar there are used one or more coupling elements. Each of these elements comprises a plate 8 which can have one corner portion removed to define an arcuate edge 9 so proportioned as to snugly embrace a portion of the post 1 with which it is to be assembled. An arcuate flange 10 is extended downwardly

from said edge and is adapted to be seated in a portion of the recess 5 and, in order to hold the flange against longitudinal movement within said recess, it has an outwardly or laterally extended lug 11 proportioned to fit in one of the notches 6. Extending from the respective ends of the flange 10 are connecting flanges 12 located at the adjacent edges of the plate 8 and each of these connecting flanges is cut away along its bottom portion, as indicated at 13 so as to clear the upper edge of the collar 2 when flange 10 is mounted in the recess 5. This is clearly disclosed in Figure 3. A tongue 14 is extended from each of the flanges 12 and these tongues are offset laterally relative to said flanges so that when the two flanges 12 and plates 8 are assembled one beside the other, the tongues 14 at the meeting edges of the plates will cooperate to define a slot 15.

It is to be understood that the plate 8 can be 20 of any desired size and outline. In the structure illustrated, these plates are so proportioned that four of them can be extended in the same plane about a supporting post, the flanges 10 being extended through 90 degrees. Obviously, 25 however, the shapes of the plates and the lengths of their depending flanges 10 can be so modified that the number of plates which can be arranged around a post at a given point can be increased or reduced.

In practice, a pair of plates 8 can be positioned 30 with opposite tongues in engagement with opposite faces of a pair of opposed angle strips 15 and, by means of rivets 16 or the like these parallel contacting angle strips 15 can be held together and to the tongues 14 within the slot 15 defined by the tongues. See Figure 2.

Another pair of coupling elements, one of 40 which has been shown in Figure 5, is then assembled with the other ends of the strips 15 as before explained so that a bridging unit comprising two pairs of coupling elements and a connection between said elements thus is produced. Any desired number of these bridging units can be assembled, depending upon the 45 number of shelves to be mounted between the posts 1. After the various bridging elements have been assembled with the collars on the posts, the shelves to be supported and which have been indicated at S, are placed on the angle strips and on the plates 8 at the ends of the shelves. If preferred, the strips 15 and the plates 8 can, in themselves, constitute shelves. Obviously the shelves and/or their bridging elements can be quickly assembled with the collars 2 simply by lowering the flanges 10 into the

adjacent grooves 5 and they can easily be removed simply by reversing that operation. When the bridging elements are in engagement with the supporting collars they serve as rigid connections between the posts so that the posts thus connected can be supported on end without requiring any special fastening means at the bases. Thus the shelf arrangement is particularly useful in show cases, show windows and wherever it is desired to provide support for merchandise or the like to be displayed. It will be understood that it is not necessary always to completely encircle a post with coupling units such as shown in Figure 5. If preferred, these units can be mounted singly, in pairs, etc., so that it is thus possible to set up various combinations of shelves and to support one or more shelves on each post.

The parts are inexpensive to manufacture, can be made of a light metal and are easily handled because of the interchangeability of the parts as well as the other advantages pointed out, and the invention has many applications not possible with the usual types of knockdown shelving.

What is claimed is:

1. In a shelving structure a post, a collar adjustably mounted thereon providing an annular recess in its upper end, plates each having a cut out at one corner adapted to embrace the post, a flange depending from each plate adjacent the cut out portion and adapted for insertion into the recess, tongues extending from the bottoms of the plates and cooperating to form slots between tongues on adjacent plates, and shelf engaging means secured within the slots.

2. In shelving a post, a collar thereon providing an annular recess in its upper surface and having a notched wall, coupling elements each including a plate having a cut out at one corner adapted to embrace the post, means depending from the plate adjacent the cut out portions and adapted for seating in the recess and engagement in said notched wall, and a pair of spaced tongues extending laterally from the plate cooperating to form a slot between tongues of adjacent coupling elements, for attachment of bridging elements to the cooperating tongues.

3. Shelving including posts, collars mounted thereon each having an annular recess in the upper end and provided with a notched wall, coupling elements having cut out portions adapted to embrace the post arranged in pairs, the elements of each pair overlying one of the collars, flanges depending from the elements adjacent the cut out portions of each pair and

adapted for insertion into the recess in the collar thereof, means on each flange for insertion into one of the notches, a pair of tongues on each of the coupling elements adapted to provide a slot between tongues on adjacent coupling elements, and bridging elements connecting the pairs of coupling elements, said bridging elements being extended into and secured within the slots defined by the tongues of the respective pairs.

10 4. Shelving including spaced posts, collars adjustably mounted thereon, each collar having an annular recess with a notched wall, coupling elements arranged in pairs, each element including a plate having a cut out at one corner adapted to embrace the post, an arcuate flange depending from the plate adjacent the cut out and adapted to be seated in the recess in one of the collars and a lug on the flange for insertion into one of the notches, a pair of tongues on the coupling elements cooperating to provide a slot between tongues on adjacent coupling elements, and bridging elements connecting the pairs of coupling elements, said bridging elements being extended into and secured within the slots defined by the tongues of the respective pairs.

20 5. In shelving, a post, a collar adjustably mounted thereon and having its wall flared to define an annular recess between the post and said wall, there being spaced notches formed in the wall, and a plurality of coupling elements mountable on the collar, each including a plate having a cut out at one corner adapted to embrace the post, an arcuate flange depending from the plate adjacent the cut out and adapted for seating in the annular recess, a lug on the flange engageable in one of the notches, and a pair of spaced tongues laterally extended from the plate cooperating to provide a slot between tongues on adjacent coupling elements, for attachment to adjacent coupling elements of bridging means insertable into the slots.
